COMPACT

Abraham E. Chesler, Brooklyn, N. Y.

Application October 12, 1934, Serial No. 748,055

14 Claims. (Cl. 132—83)

My present invention relates primarily to powder compacts, although certain of the features thereof are applicable in other relations.

It is among the objects of the invention to provide a powder compact of attractive and rich appearance, which may yet be made from relatively inexpensive parts, easily assembled without great expense.

Another object is to provide a thoroughly serviceable compact of the above type of exceptionally rugged construction, and not apt to become scratched or marred or broken under conditions of use.

Another object is to provide a compact which affords excellent mirror facilities both when the compact is closed and when opened during use.

In the accompanying drawing in which is shown one of various possible embodiments of the several features of the invention,

20 Fig. 1 is a perspective view of one embodiment of the compact in closed position,

Fig. 2 is a dropped perspective view of the constituent elements thereof,

Fig. 3 is a fragmentary cross-sectional view 25 on a larger scale, taken on line 3—3 of Fig. 1,

Fig. 4 is a detail fragmentary view of the hinge between the cup and the bezel, and

Fig. 5 is a detail sectional view taken on line 30 5—5 of Fig. 2.

Referring now to the drawing, the compact includes a rigid body preferably of vitreous material, which may include a back element comprising a silver-backed glass plate 10 preferably beveled at 10' and a face element comprising a 35 thicker annular body 11 preferably of a vitreous material, which may also be of glass, peripherally beveled at 11', and having preferably a gunmetal or other colored mirror back. The two elements 10 and 11 making up the body are securely bonded together preferably by an annular sheet 12 of celluloid which may be covered with shellac and the adhesiveness of which is developed by compressing these elements together.

40 The powder receptacle 13 is a flat sheet metal cup snugly fitting the inner periphery 14 of the annular face element and provided with a rim 15 engaging the front of the face element and with an outer bead 16 protruding outwardly and contacting said face element at its outer rim 16'. The cup is firmly secured in the body, preferably by interposed plastic cement 17.

45 The cup 13 is provided with a cover, usually a hinged cover. Preferably this cover includes a sheet metal bezel B which may conveniently be made of two pieces including an inner or body

piece comprising a flat ring 18 with a skirt 19 from the inner periphery thereof and an outer or frame piece crimped about the ring as at 20 and having an inturned, preferably an obliquely in-turned flange 21. Preferably, the inner or body piece has a looped tongue 22 protruding through a corresponding gap 23 in the crimped conformation of the frame piece 20 and encircling a pintle pin 24 retained under the bead 16 by loops or eyes 25 integral with said bead. Diametrical- 5 . . . . .

ly opposite the hinge loop 22 the ring 18 has an integral finger tab 26 protruding through a corresponding gap 27 in the crimped edge 20 of the frame piece. The bezel skirt 19 also has a snap protuberance 40 immediately below finger tab 26, 10 coacting with a corresponding depression or aperture 41 in the cup 13 to hold the cover closed by a spring snap action.

Locked within the bezel are a pair of rigid plates 29 and 30 in back to back relation. The outer plate 29 preferably is beveled at 29' to engage the inturned flange 21 of the bezel. The inner plate 30 which is also preferably beveled at 30' is locked in position by a sheet metal lock ring 31, preferably provided with a concentric 20 groove formation 32 affording resiliency and engaging the skirt 19 at its outer peripheral face, the inner flat edge of said ring engaging the bevel 30' of the inner plate.

Adequately to lock said plates within the bezel, 30 it is preferred to interpose one or more sheet metal cross pieces therebetween. These cross pieces may be strips of brass 33 of length somewhat greater than the diameter of the bezel, preferably ground as at 33' at their extremities, each 35 of which cross pieces may be inserted in the bezel by introducing its ends, bowing the intervening length of the strip and causing said strips to snap in position when the two plates 29 and 30 are pressed home. By this means, the intervening lock strip 33 tends resiliently to push the two plates 29 and 30 apart. The plates are thus securely retained between the inturned flange 21 and the lock ring 31 without the slightest movement or looseness. 45

As shown in the drawing, two such thin metal strips 33 and 34 may be interposed at right angles to each other, or, if desired, a unitary spider with three, four or more radial arms may be used to advantage. 50

In the preferred embodiment, the inner beveled plate 30 is a glass mirror having a silvered-back. While the outer beveled plate 29 may be of any suitable material, preferably vitreous, it is desirable to form this member also of glass. 55

For ornamental effect, the outer glass plate 29 may be coated at its inner face with a suitable paint or enamel. In a desirable construction, the inner face of said plate has a central depression 35 which may be silvered prior to application of the paint or enamel backing. Thus, the front of said plate has a polished enamelled metal-like appearance, although the exposed face is of glass plate and therefore not subject to scratching, 10 chipping or other injury to the paint or enamel coating at the protected inner face.

Preferably, one of the lock strips 34 extends along the depression 35 and the major portion of its thickness is thus lodged within the thickness of the outer plate 29, thereby rendering the cover construction flatter than it otherwise would be. In a desirable construction the strip 34 alone is used, its ends being accommodated at the gaps in the bezel provided by hinge loop 22 and finger tab 26.

Within the cup 13 is disposed the supply of powder 36 over which is superposed the usual framed sift disk 37 on which lies the conventional powder puff 38 pressed home by the mirror plate 25 30 when the device is closed.

By the arrangement disclosed, the back of the device constitutes a serviceable mirror, accessible without the need for opening the compact, while in use, the compact when opened, exposes the 30 mirror at the back of the cover.

It will of course, be understood that the skirt 19 of the bezel could be duplicated at the front face thereof, and each of the plates 29 and 30 could be separately locked in place by duplication 35 of the lock ring 31 to retain the outer plate in place.

It will be clear that the bezel arrangement for the plates 29 and 30 is of more general application in relations other than for compact covers, 40 although it finds its preferred utility for the latter use.

The powder compact is shown circular, but it is clear that it could be made hexagonal or of any other ornamental design.

45 It will thus be seen that there is herein described an article in which the several features of this invention are embodied, and which article attains the various objects of the invention and is well suited to meet the requirements of practical use.

As many changes could be made in the above construction, and many apparently widely different embodiments of this invention could be made without departing from the scope thereof, it is 55 intended that all matter contained in the above description or shown in the accompanying drawing shall be interpreted as illustrative and not in a limiting sense.

Having thus described my invention, what I 60 claim as new and desire to secure by Letters Patent is:—

1. A powder compact comprising a vitreous body having a closed bottom, a sheet metal cup cemented in a corresponding depression in the 65 top of said body and having an upstanding rim bead exposed at the face of said body.

2. A compact comprising a non-metal body including a mirror back plate and a non-metal annular face plate, cemented to said back plate, 70 a sheet metal cup fitting within said face plate, pressed against the back of said mirror plate and cemented in place, said cup having an exposed rim.

3. A powder compact comprising a body including a mirror back element and an annular

face element, adhesive means bonding said elements together and a sheet metal cup fitting in said face element and held in place by plastic cement.

4. A powder compact comprising a body including a mirror back element and an annular face element, an intervening sheet of celluloid and shellac bonding together said elements and a sheet metal cup fitting in said face element and held in place by plastic cement. 5

10 5. A compact unit comprising a body including a silvered mirror back element, a colored mirror annular face element, an annular celluloid cement bond connecting said elements into a unitary body, a sheet metal cup lodged in said body and cemented against the back of said mirror element, said cup having a bead overlapping the inner periphery of the face element.

6. An article of the character described, comprising a cover member comprising a bezel, two 20 rigid plates lodged in back to back relation in said bezel, a lock member intervening between said plates and engaging said bezel and a lock ring lodged in the rim of said bezel and contacting one of said plates. 25

7. An article of the character described, comprising a bezel, rigid bevelled plates lodged in said bezel in back to back relation, one or more sheet metal members interposed between said plates, tending to urge them apart and means at the re- 30 spective rims of said bezel, locking said plates against movement relative to said bezel.

8. An article of the character described, comprising a bezel, rigid bevelled plates in back to back relation in said bezel, a soft metal strip of 35 length greater than the diameter of said bezel, engaged at its ends with said bezel and reacting against the adjacent faces of said rigid plates, said bezel having means at the opposite faces thereof in contact with the bevelled rims of the 40 respective plates to lock the same in position.

9. An article of the character described, comprising a bezel, having an inturned flange at one 45 face and a cylindrical skirt at the other, a rigid bevelled plate in said bezel engaging said inturned flange, a sheet metal lock member against the back of said bevelled plate, a bevelled mirror in the cylindrical skirt of said bezel and a lock ring frictionally fitted in said skirt and engaging the bevel of said mirror.

10. An article of the character described comprising a sheet metal bezel, vitreous bevelled plates in back to back relation within said bezel, a brass strip of length somewhat greater than the diameter of said bezel, extending diametrical- 55 ly thereacross and lodged at its ends in said bezel and tending to push said plates apart, said bezel having an obliquely inturned flange engaging the bevelled rim of one of said plates and a lock ring friction-fitted in said bezel and engaging the 60 bevelled rim of the other plate.

11. An article of the character described comprising a bezel, a vitreous bevelled plate held in said bezel, having a silvered depression in the middle of its back, a transverse metal strip of 65 length somewhat greater than the diameter of said bezel, lodged at its middle in said depression and engaging said bezel at its ends, a bevelled mirror in back to back relation with said bevelled plate and a lock ring engaging the bevel 70 of said mirror and retained in said bezel.

12. An article of the character described comprising a bezel having an obliquely inturned flange at one face thereof, a vitreous member having a bevelled edge engaging said inturned flange, said 75

vitreous member having a depression near the middle of its back, a brass locking structure comprising two or more diametrical arms angularly spaced, of length greater than the diameter of said bezel and locked at their respective ends in said bezel, one of said arms extending into said depression, a bevelled mirror engaging said locking structure and a crimped lock ring frictionally engaging said bezel at its outer periphery and the bevelled edge of said mirror at its inner periphery.

13. In an article of the character described, a sheet metal cup having a cylindrical wall with a beaded rim, a cover bezel hinged to said rim, said bezel comprising a skirted flat disk body, said disk having an integral finger tab and a hinge loop protruding therefrom, the latter lodged in

a corresponding gap in said beaded rim, an arcuate pintle extending through said hinge loop and retained by said rim, said bezel including a complementary annular frame piece crimped at its rim about said disk and exposing said finger tab and said hinge loop, said frame piece having an inturned peripheral flange. 5

14. A powder compact comprising a body including a reflecting back element and an annular face element, adhesive means bonding said elements together, said body determining a well for containing powder, said well of height substantially equal to the thickness of said annular face element and of base area substantially that of the opening in said annular element. 10 15
